UNITED STATES PATENT OFFICE.

SAMUEL J. SPURGEON, OF HOUSTONIA, MISSOURI.

CIRCUIT-CLOSER FOR TELEGRAPH-KEYS.

SPECIFICATION forming part of Letters Patent No. 293,105, dated February 5, 1884.

Application filed October 31, 1883. (No model.)

To all whom it may concern:

Be it known that I, SAMUEL J. SPURGEON, of Houstonia, Pettis county, Missouri, have invented a new and Improved Circuit-Closer 5 for Telegraph-Keys, of which the following is a full, clear, and exact description.

The object of my invention is to provide a new and improved attachment for telegraph-keys, whereby the circuit will be closed automatically when the key is released.

This invention, which is an improvement on the circuit-closer for telegraph-keys for which United States Letters Patent No. 284,508 were issued to me on the 4th day of September, 1883, 15 consists in the combination, with a telegraph-key, of a circuit-closing spring or lever pressed against the bottom of the key, which circuit-closing lever is pressed downward to break the circuit when the key-button is depressed 20 by a button and stem held loosely on the button of the key, all as hereinafter fully described, and pointed out in the claims.

Reference is to be had to the accompanying drawings, forming part of this specification, in 25 which similar letters of reference indicate corresponding parts in all the figures.

Figure 1 is a plan view of a telegraph-key provided with my improved circuit-closer. Fig. 2 is a longitudinal sectional elevation of 30 the same, and Fig. 3 is a plan view of the circuit-closing spring.

The telegraph-key A is mounted on a shaft, B, journaled in standards C on the base-plate C', and is pressed upward by a spring, 35 D. The button E is provided in its top with a recess, F, into which a button, G, fits, which is provided with a downwardly-projecting stem, H, passing through a longitudinal aperture, J, in the button E, the lower end of 40 the stem H resting on the free end of a spring or circuit-closer, K, provided at its opposite end with a longitudinal slot, L. The stem H is provided with a longitudinal slot, H', through 45 which a transverse pin, J', in the button E passes, which pin holds the stem H in the button E, but permits of an up-and-down movement of the stem in the said button E. The key A is provided on its bottom with a plati- 50 num contact-point, a, adapted to come in contact with a contact-point, b, on the free end of

the spring K. A pin, M, passes through the slot L of the spring K, and holds the spring on the base by a screw, N, screwed into it from the bottom. An insulating-collar, O, is placed in the base-plate C', and insulates the pin M and the spring K from the base-plate C'. When the key is not used for telegraphing, the points a b are in contact and the circuit is closed between the screw N and the base-plate C', which are connected with the opposite ends of the line. If the key is to be used for telegraphing, the circuit must be broken. If the finger is placed on the button E, it first presses the button G downward, so 65 that its upper surface will be flush with the top of the button E. Thereby the stem H will press the free end of the spring K downward, and thus break the contact between the points a b, whereby the circuit will be broken, as desired. The circuit is broken automatically and is closed automatically as soon as the finger is removed from the button. The slot L permits of adjusting the spring K according to the length of the key.

In place of the points a b, other contact-surfaces may be provided on the spring K and the key A.

The above-described circuit-closer can be applied to any telegraph-key.

Having thus described my invention, I claim as new and desire to secure by Letters Patent—

1. The combination, with a telegraph-key, A, having a recess in its button E, of the circuit-closing spring or lever K, the button G, 85 held loosely in the recess of the button E, the stem H, having a slot, H', and the pin J', substantially as herein shown and described.

2. The combination, with a telegraph-key, of the circuit-closing spring or lever K, having a slotted end, the pin M, passing through the slotted end of the lever K, the insulating-sleeve O, the screw N, the button G, held loosely in the button E, and the stem H on the button G, substantially as herein shown 95 and described.

SAMUEL J. SPURGEON.
